United States Patent Office

Des. 208,514
Patented Sept. 5, 1967

208,514

FACIAL STEAM APPLICATOR

Donald S. Hartwell, Providence, R.I., assignor to Sheffield Laboratories, Inc., Boston, Mass., a corporation of Massachusetts

Filed July 21, 1966, Ser. No. 3,165

Term of patent 14 years

(Cl. D83—1)

Fig. 1.

Fig. 2.

Fig. 3.

Fig. 4.

Fig. 5.

FIGURE 1 is a side elevation of the facial steam applicator showing my new design, the side opposite being substantially the same;

FIGURE 2 is a front elevation thereof;

FIGURE 3 is a rear elevation thereof;

FIGURE 4 is a top plan view thereof; and

FIGURE 5 is a bottom plan view.

I claim:

The ornamental design for a facial steam applicator, as shown and described.
